UNITED STATES PATENT OFFICE.

JAMES H. MONTGOMERY, OF DENVER, COLORADO.

CRUSHING-ROLLS.

SPECIFICATION forming part of Letters Patent No. 727,177, dated May 5, 1903.

Application filed August 11, 1902. Serial No. 119,311. (No model.)

To all whom it may concern:

Be it known that I, JAMES H. MONTGOMERY, a citizen of the United States of America, residing at Denver, in the county of Arapahoe and State of Colorado, have invented a new and useful Improvement in Crushing-Rolls, of which the following is a specification.

My invention relates to improvements in crushing-rolls, more particularly those used for crushing rocks, clays, and like materials.

The objects of my improvements are to provide rolls with housings pivotally connected to a base-frame and mechanism to prevent one housing advancing or receding without the other, each housing carrying a crushing-roll and springs and adjusting-rods to keep the rolls in crushing contact. I attain these objects by the mechanism illustrated in the accompanying drawings on three sheets, in

which—

Figure 1 is a side view. Fig. 2 is an end view. Fig. 3 is a plan; Fig. 4, a cross-section through the center longitudinally. Fig. 5 shows the rolls when open for inspection and repairs; Fig. 6, an enlarged section of the lug M, showing spring-rod I and adjustments; Fig. 7, an enlarged section of the box B', showing method of adjusting; Fig. 8, the spring-rod and springs.

Similar letters refer to similar parts in the several views.

The rolls are constructed with a base-frame A, on one end of which are the boxes B B and on the opposite end the boxes B' B', which are adjustable, so the rolls may more easily be placed in a parallel position. I prefer to make this box as shown in enlarged section in Fig. 7. The box B' has the shaft C placed in position, the shims R, of which a sufficient number are used to bring the shaft C exactly parallel with the shaft C, resting in the boxes B B in the opposite end of the frame A. The key Q is then drawn tight with the nuts Q', which firmly holds the shaft and shims in place.

The roll-supporting housings D D are so constructed that their backs and sides form a dust-proof housing, which prevents dust from filling the room when crushing dry material. They are also provided with journal-boxes E E on their lower part, which, together with the shafts C C and boxes B B

and B' B', form the hinges, which permit the housings D D being laid back, as shown in Fig. 5, for inspection of the rolls, repairing, or cleaning.

The rolls Z are placed inside the roll-supporting housings D D, and their shafts Y are journaled in the boxes G G G G on the sides of the roll-supporting housing D, being held in place by the caps G' G'. To provide for the rolls advancing and receding in unison, the segmental gear-teeth F F F on each side of the roll-carrying housings D are so constructed that the pitch-lines formed by the radial lines radiating from the center of the boxes E are tangent. Thus the rolls must advance and recede while in a parallel position with each other, the housing hinging on the shaft C. The rolls are held in crushing contact by the springs J and the spring-rods I, which pass through the slot-holes in the lugs M on the roll-housings D and shown more particularly in enlarged section, Fig. 6. On these spring-rods and between the nuts L and the lugs M is a rubber cushion X to take up the shock of the recoil of the rolls after the passage of the gads, pick-points, and other uncrushable substances that may accidentally be left in the ore.

The feed-hopper U is provided with supporting-brackets T on each side, which rest upon the roll-carrying housings D, its point projecting below and to near the point of contact of the rolls.

The rolls are driven by band-wheels placed on their shafts Y and shown in the drawings in Fig. 3 and travel in the direction of the arrow-points. When the rolls are in operation, the spring-bars I and springs J draw the rolls together. The exact size to which the material is to be crushed to is governed by distance. The rolls are held apart by the adjusting-nuts L and L', and when by accident uncrushable substances—such as pick-points, gads, &c.—be fed with the other material to the rolls the springs J will permit the receding of the rolls and after the passage returning the rolls to their normal position, the shock of the recoil being relieved by the rubber cushions X, the roll-housings operating in unison and being held in perfect alignment by the segment of gears F F F.

Having described my invention and its op-

eration, what I claim as new, and desire to secure by Letters Patent, is—

1. A base-frame A, having boxes B B on one end, and boxes B' B' on the opposite end, and carrying shafts C; two movable roll-carrying housings D, having the boxes E on their lower part, and the lugs M on their upper part, the journal-boxes G and the caps G', and the segmental gear-teeth F F F, and each housing carrying a crushing-roll; the spring-rods I, the springs J, and the feed-hopper U, all substantially as set forth and described.
2. A base-frame; two movable roll-carrying housings fulcrumed on the base-frame, each carrying segmental gear-teeth F F F meshing together and a roll-shaft journaled in each housing; adjustable rods and springs for drawing the housings toward each other, thereby holding the rolls in crushing contact, all substantially as set forth and described.
3. A base-frame; two roll-carrying housings,

ings, each pivotally secured to the base-frame and each carrying a crushing-roll, segmental gear-teeth F F F on each housing, the spring-rods I, springs J, lugs M, nuts L and L' and the rubber cushions X, all substantially as described and for the purposes set forth.

4. The combination of a base-frame; two movable roll-carrying housings, each carrying a crushing-roll and each pivotally connected to the base-frame; spring-rods and springs for drawing the housings together, thereby holding the rolls in contact and adapted to be laid back for inspection when the spring-rods and springs are removed, as shown in Fig. 5, all substantially as set forth and described.

JAMES H. MONTGOMERY.
